UNITED STATES PATENT OFFICE.

REINHOLD KOBAN, OF EDGEWOOD PARK, MISSOURI, ASSIGNOR TO NORVELL-SHAPLEIGH HARDWARE COMPANY, OF ST. LOUIS, MISSOURI, A CORPORATION.

WEDGE.

No. 903,583.

Specification of Letters Patent. Patented Nov. 10, 1908.

Application filed March 18, 1908. Serial No. 421,782.

To all whom it may concern:

Be it known that I, REINHOLD KOBAN, a citizen of the United States of America, residing in Edgewood Park, in the county of St. Louis and State of Missouri, have invented certain new and useful Improvements in Wedges, of which the following is a full, clear, and exact description, reference being had to the accompanying drawings, forming part of this specification.

My invention relates to a wedge for service in holding tools, such as axes, hatchets and hammers provided with eyes, to their handles, the wedge being so produced as to provide for the retention thereof in the handle in which it is introduced without the employment of any agency other than that contained in the wedge itself.

Figure I is in part an elevation and in part a section of an ax applied to its handle or helve and my wedge in position for holding the ax upon the handle. Fig. II is an end elevation of the part shown in Fig. I. Fig. III is a longitudinal section taken on line III—III, Fig. IV. Fig. IV is a longitudinal section taken on line IV—IV, Fig. I. Fig. V is a perspective view of my wedge.

In the accompanying drawings: A designates an ax provided with the usual eye B and C is the wooden handle seated in the eye of the ax.

1. designates my wedge which is provided at its inner end with a knife edge 2. At one side of the wedge and extending from its butt to a point between the butt and the knife edge of the wedge is a groove 3 that leads to an opening 4 extending through the wedge, thereby providing a knife member 5 which terminates at the top of the opening 4 in a cutting edge 6. At the side of the wedge opposite to that at which the groove 3 is located is a groove 7 that extends inwardly from the knife edge 2 of the wedge and terminates at the bottom of the opening 4 and in a position off-set laterally from the cutting edge 6 at the top of said opening. The termination of the groove 7 is preferably in alignment with the knife edge 2 of the wedge to provide a cutting edge at the bottom of the groove and the existence of this cutting edge at the point named is made possible by extending said groove into the knife edge of the wedge in a manner to pro-

vide a notch in the knife edge of the wedge, as seen in Figs. I and V.

When the wedge is driven into a tool handle for the purpose of seating it therein in the positions shown in the drawings, a splinter C' is cut from the wood of the tool handle which is split by driving the wedge into place, the production of this splinter being due to the wood from which the splinter is made riding in the groove 7 at one side of the wedge until it reaches the opening 4 in the wedge and then passes through said opening into the groove 3 at the opposite side of the wedge. At this time the wedge is cut into the splinter C' which enters into and passes upwardly in the groove 3, thereby causing said splinter to serve as a retaining member for the wedge. The groove 3 is inclined relative to the width of the wedge as most clearly seen in Fig. I, and as a consequence of its being so inclined, the splinter is carried laterally in the wedge to increase the binding or retaining action of the splinter, due to its being thrown at an angle to the point at which its inner end is joined to the tool.

I preferably provide two sets of the grooves hereinbefore described in the wedge for additional increased support in the holding of the wedge by two splinters instead of a single splinter produced from the tool handle and in so doing the second groove 85 designated 3' corresponding to the first groove 3 is located at the reverse side of the wedge relative to that at which the groove 3 is located and the second groove designated 7' is located at the reverse side of the wedge 90 relative to the side at which the groove 3' and the groove 7 is located. The opening 4' provides communication between the grooves 3' and 7' and a knife member 5' similar to the knife member 5 and having a cutting edge 6' at its inner end extends to the opening 4'. It will be seen that by locating the grooves 3' and 7' reversely relative to the grooves 3 and 7, I provide for the production of retaining splinters C' which extend 100 to opposite sides of the wedge and which have oppositely directed influences for the retention of the wedge in the tool handle.

I claim:

1. A wedge of the character described having an opening therein intermediate of

- its ends, a cutting edge at the top of said opening, and a groove extending from the inner end of the wedge to said opening, substantially as set forth.
5. 2. A wedge of the character described having an opening therein intermediate of its ends, a groove tapered at and leading from said opening toward the outer end of the wedge and inclined relative to the width 10 of the wedge, and a groove extending from the inner end of the wedge to said opening, substantially as set forth.
3. A wedge of the character described, having two openings therein intermediate of 15 its ends, grooves tapered at and leading from said openings toward the outer end of the wedge, one of said grooves being located at one side of the wedge and the other groove being located at the other side of the wedge, being located at the other side of the wedge, 20 and lower grooves extending from the inner ends of the wedge at the sides thereof to said opening, substantially as set forth.
4. A wedge of the character described, having two openings therein intermediate of 25 its ends, upper grooves leading from said opening toward the outer end of the wedge, one of said grooves being located at one side of the wedge and the other groove being located at the other side of the wedge, and 30 lower grooves extending from the inner ends of the wedge at the sides thereof to said
- opening; said wedge being provided with cutting edges at the tops of said openings, substantially as set forth.
5. A wedge of the character described, 35 having two openings therein intermediate of its ends, upper grooves leading from said openings toward the outer end of the wedge; one of said grooves being located at one side of the wedge and the other groove being located at the other side of the wedge, and lower grooves extending from the inner ends 40 of the wedge at the sides thereof to said opening; said wedge being provided with cutting edges at the tops of said openings, 45 and said grooves being inclined relative to the width of the wedge, substantially as set forth.
6. A wedge of the character described, having an opening intermediate of its ends, 50 a groove extending from the inner end of the wedge to said opening at one side of the wedge, and a groove extending from said opening toward the outer end of the wedge and located at the side of the wedge opposite 55 to that at which the first named groove is located, substantially as set forth.

REINHOLD KOBAN.

In presence of—

E. S. KNIGHT,
BLANCHE HOGAN.
